SHOE PRESS

Peter J. Elkes, High Point, N. C.

Application November 16, 1951, Serial No. 256,796

1 Claim. (Cl. 12—37)

1
The present invention relates to a shoe repairman's press and more particularly to a press for joining a half sole to the shank of a shoe being repaired.

In the conventional method of half-soling of shoes it is customary to separate the worn forward sole portion of the shoe sole from the shoe upper as far back as the shank of the shoe sole and then to cut the sole across the shoe at the junction of the forward worn portion of the sole with the shank. The cut edge of the shank is then bevelled or feathered and the half-sole is then affixed to the shank by the use of nails. By thus joining the half-sole to the shank, the row of nail heads which are visible when the sole of the shoe is visible produces visible evidence of the repair.

The primary object of this invention is to facilitate the production of an invisible junction between a half-sole and a shoe so as to give no visible indication of the repair.

Another object of the present invention is to clamp a half-sole which has been cemented to a repaired shoe and to retain the parts in clamped position for a period of time sufficient for the cement to set and harden without interfering with the repairing of other shoes in the same manner.

A still further object of the present invention is the provision of means for locking the rotor and releasing it.

The above and other objects may be attained by employing this invention which embodies among its features an anvil upon which is supported a shoe from which a worn portion of the sole has been cut and to the shank of which a half-sole is to be cemented, a clamp plate mounted to move forward and away from the anvil for exerting pressure on the junction of the half-sole and the shank.

Other features include a rotor mounted to rotate about a horizontal axis, peripherally spaced clamp plates carried by the rotor for movement radially toward and away from the rotor, and anvils mounted on the rotor to move about peripherally spaced horizontal axes from radial positions between the rotor and the clamp plates to other positions which will facilitate the mounting of shoes on the anvils.

In the drawing—

Figure 1 is a front view of a shoe repairman's piece embodying the features of this invention.

Figure 2 is a side view of the piece illustrated in Figure 1, certain portions being broken away to illustrate certain details of construction.

2

Figure 3 is a fragmentary side view of the rotor with portions being shown in section.

Figure 4 is a plan view of one of the clamp plates, and

Figure 5 is a side view of a clamp plate moving screw and hand wheel.

Referring to the drawing in detail, a bed 10 is provided with spaced parallel upwardly extending arms 12 which are provided adjacent their upper ends with aligning openings for the reception of a transversely extending axle shaft 14 which lies along a horizontal axis.

Mounted for rotation on the axle shaft 14 between the arm 12 is an elongated rotor 16 which is preferably square in cross section to provide elongated adjacent faces 18 which lie perpendicular to one another. Carried by the rotor 16 midway between opposite ends thereof are outwardly extending radial guide bars 20 which are located substantially midway between opposite longitudinal side edges of their respective adjacent faces 18. Outwardly extending radial arms 22 are carried by the rotor 16 adjacent opposite ends thereof and these arms lie in spaced parallel relation to the guide bars 20.

Bridge pieces 24 are carried by the arms 22 and extend transversely therebetween at the ends of the arms 22 remote from the rotor 16 and these bridge pieces 24 are attached in any suitable manner to the ends of the guide bars 20 remote from the rotor 16. Elongated guides 26 are carried by the arms 22 adjacent the bridge pieces 24 and extend toward the rotor 16 in spaced parallel relation to the guide bars 20. Formed in the bridge pieces 24 on opposite sides of the guide bars 20 and midway between the guides 26 and the guide bars 20 are internally screw threaded openings 28 the purpose of which will hereinafter appear.

Mounted for sliding movement on opposite sides of the guide bars 20 and on the guides 26 are elongated clamp plates 30 having notches 32 in opposite ends for receiving the guide bars 20 and guides 26 and swivelly connected to the clamp plates 30 intermediate the ends thereof are screw threaded stems 34 which extend through and threadedly engage the openings 28. A hand wheel 36 is carried by each stem 30 adjacent the end thereof remote from its respective clamp plate 30 by means of which the stems 34 may be rotated to advance or retract the clamp plates 30 relative to the rotor 16.

Carried by each face 18 of the rotor 16 are outwardly extending pairs of ears 38 having aligning openings extending therethrough for the re-

ception of pivot pins 40 by means of which anvils designated generally 42 are rotatably coupled to the rotor 16. Each anvil comprises a base portion 44 having a flat bottom surface which is adapted to engage a face 18 of the rotor 16 to hold its respective anvil perpendicular to the axis of the rotor and in alignment with a clamp plate 30 when the anvil is in shoe holding position, an elongated shank portion 46 which extends outwardly from the base portion 44 and perpendicular to the flat bottom surface, and a last 48 having a flat top or outer surface 50 upon which the junction of the shank of a shoe and a half sole is supported. As illustrated in Figure 2 the anvils 42 are tilttable about their respective pivot pins 40 from positions in which they lie radial to the rotor 16 and between the clamp plates 30 and the rotors 16 to angular positions angular thereto as will be readily understood upon reference to Figure 2.

Mounted on the outer face of one of the upwardly extending arms 12 is a housing 60 in which is mounted a plunger 62 having a flanged portion 64 adjacent one end. Encompassing a portion of the plunger is a spring 66, one end 68 being seated on the bottom wall of the housing, the opposite end 70 abutting the flange 64. To the lower end of the plunger there is connected one end of cable 72, the opposite end being connected to a treadle bar 74 that is pivotally mounted at 76 to one of the upwardly extending arms 12. The treadle bar is provided with an L-shaped element that engages a slot 80 in one side edge of one of the arms 12 to limit upward movement of the treadle bar. On one end of shaft 14 there is mounted a disc 82 having diametrically opposed slots 84 that are adapted for engagement by the plunger end 86.

In use, a shoe which has been prepared for half-soling is placed in an inverted position over a last 48 which has been moved out of position beneath its respective clamp plate 30 and cement is applied to the bevelled or feathered edge of the shank of the sole. A half-sole which has been bevelled or feathered in the opposite direction is then placed on the last with its bevelled or feathered edge engaging the bevelled or feathered edge of the shank. With the half-sole thus positioned relative to the shoe, the anvil 42 upon which it is mounted is moved about its pivot 40 so as to extend radially between the rotor 16 and a clamp plate 30. Upon the turning of the hand wheel 36 of the plate 30 adjacent the shoe to advance the plate toward the rotor 16, the joined edges of the shank and half-sole will be firmly pressed together. If additional shoes are to be repaired the operator places his foot on the treadle bar 74 and pushing downwardly causes the cable 72 to exert a downward pull on the plunger 62 which

disengages the plunger head or end 86 from one of the slots 84 and allows the operator to rotate the rotor to bring a pair of anvils in position to receive shoes to be repaired, and when the pair of anvils are in position the operator releases the foot treadle bar which assumes its neutral position due to the spring 66, the head 86 of plunger 62 engaging one of the slots 84 thus locking the rotor in the desired position.

From the foregoing description, when taken in connection with the accompanying drawing, the advantages of the construction and operation will be apparent to those skilled in the art to which the invention appertains, and I desire to have it understood that the device shown is merely illustrative and that such changes may be made within the scope of the claim hereto appended.

What is claimed is:

In a press for half-soling shoes a bed frame, spaced parallel upstanding arms carried by the bed frame, a rotor carried by the arms to rotate therebetween about a horizontal axis, groups of parallel peripherally spaced guides carried by the rotor and extending radially therefrom, clamp plates carried by the guides for movement toward and away from the rotor along axes which lie radial thereto, anvils carried by the rotor for movement about peripherally spaced horizontal axes from positions between the rotor and the clamp plates in which they lie radial to the rotor to positions in which they lie other than radial to the rotor, said axes being parallel with the axis of said rotor, hand actuated means carried by the guides and connected to the clamp plates for moving said plates along the guides, a notched disc on said rotor, foot actuated means for locking said rotor in said press and for releasing said rotor from a locked position, said foot actuated means comprising a treadle, a cable, and a spring operated bolt, said bolt engaging said notched disc whereby a downward movement of the treadle will cause an unlocking of said bolt from said disc.

PETER J. ELKES.
